COOLING TOWER

Norman O. Fleming, La Crescenta, Calif.

Application November 28, 1927, Serial No. 236,173
Renewed March 27, 1933

18 Claims. (Cl. 261—111)

My invention relates to liquid cooling devices and more particularly to cooling towers.

In many arts where it becomes necessary to dissipate a large amount of heat from objects at a temperature higher than that of the atmosphere, a circulation of water is maintained over these objects and through an atmospheric cooling tower. The latter includes a structure of baffle plates over which the water falls so as to become finely divided and drop a considerable distance through the atmosphere. The evaporation of the water from the surfaces of the drops into which it is divided, as these fall through the air, absorbs heat from these drops so that when the water collects at the bottom of the tower it is cooled to a temperature generally below that of the atmosphere.

These towers are usually of large size, and besides consuming valuable space they are unattractive in appearance, and constitute eyesores wherever they are installed.

It is correspondingly an object of my invention to provide a cooling tower of relatively small size for a given capacity.

25 As reliance is placed upon evaporation within the tower for cooling the water, the tower operates much more effectively when the air in the tower is replaced with fresh air from the atmosphere as rapidly as possible.

30 It is another object of my invention to provide a cooling tower in which an artificial current of air is maintained in the tower.

35 A yet further object of my invention is to provide a cooling tower in which such a current of air is set up by energy released by the falling of the water through the tower.

40 Another object of this invention is to provide a novel construction for a rotor element capable, when rotated, of circulating a medium, or capable of being rotated when contacted by a medium.

45 Further objects and advantages will be made manifest in the following description and in the accompanying drawings in which a preferred embodiment of my invention is illustrated. In the drawings:

Fig. 1 is a vertical sectional view of a preferred form of my invention.

50 Fig. 2 is a horizontal sectional view taken on the line 2—2 of Fig. 1.

Fig. 3 is a vertical sectional view taken on the line 3—3 of Fig. 1.

55 Fig. 4 is a vertical sectional view taken on the line 4—4 of Fig. 1.

Fig. 5 is a vertical sectional view taken on the line 5—5 of Fig. 1.

Figs. 6 and 7 are vertical sectional views taken on the lines 6—6 and 7—7 of Fig. 2.

Referring specifically to the drawings:

A cooling tower 10, as shown in Fig. 1, includes a frame 11, which has four main vertical posts 12 which are preferably formed of angle iron. The posts 12 are connected by horizontal frame members 13 which extend outward beyond their connection with the vertical posts 12. Supported in superimposed relation upon the extending portions of the horizontal frame members 13 are louvres 15 which surround the frame 11 so as to confine liquid which it is desired to pass downward in a spray through the cooler 10. The posts 12 may rest upon and be secured to a base 16 having side walls 17 which form a shallow container for liquid which has been passed downward through the cooler 10.

As clearly shown in Fig. 2, a cooling space 20 is formed within the frame 11 which is substantially square in cross-section. Mounted upon the horizontal frame members 13, at intervals throughout the height of the space 20, is a plurality of floors or platforms 22 which are formed of spaced stationary baffle boards 24, having ditches 25 formed in their upper surfaces so as to retain a certain amount of liquid which is dropped onto the platforms 22. The platforms 22 are thus superimposed above each other in the cooling space 20. Formed in the center of each of the platforms 22 is a circular hole 27.

Mounted in the cooling space 20, so as to be rotatable therein, is a rotor 30. The rotor 30 has a vertical shaft 31 which is axially disposed relative to the holes 27 the upper end of which is supported by an anti-friction bearing 32 mounted upon cross-bars 33 connecting certain of the horizontal frame members 13 at the upper end of the frame 11. The bearing 32 is provided with a sheet metal hood 34 which is filled with grease to provide lubrication for the bearing 32. The lower end of the shaft 31 extends into a suitable radial sleeve bearing 35 which is mounted upon the base 16.

Rigidly mounted upon the shaft 31 is a series of rotor elements 38 which are positioned so that one of the elements 38 is disposed opposite each of the platforms 22. Each rotor element 38 includes a sleeve-like hub 40 which is secured by a pin 41 to the shaft 31. Extending radially from the hub 40 are spokes 42, end portions of which are connected by horizontal braces 43 and supported by struts 44 connecting the outer ends of

the spokes 42 with the lower end of the hub 40. Mounted upon the upper surfaces of the spokes 42 and the braces 43 are impeller baffle blades 45, each of which has an upper surface 46 which 5 is inclined to the vertical. The slope of all of these blades is uniform, as measured along the horizontal braces 43, so that drops of water falling through the air and coming into contact with these blades will exert a force thereon tending to turn the rotor 30. All of the blades 45 are not, however, radially disposed relative to the axis of rotation of the shaft, but each rotor element 38 is divided into four segments, and each segment contains blades which are 10 parallel to each other and which overlap as shown in Fig. 6 to prevent any drops of water from passing through the rotor element 38 without imparting thereto the kinetic energy stored therein. The water dropping through the cooling space 20 is thus utilized for turning the 15 rotor 30.

Suitably supported on the upper end of the frame 11 is a liquid spray pipe 50 which terminates in a nozzle 51 centrally disposed in the 20 upper end of the cooling space 20 just above the upper bearing 32 of the rotor 30.

Also supported on the frame 11 in the upper 25 end of the space 20, just beneath the nozzle 51, is a stationary distributing platform 52.

Provided on a lower portion of the frame 11 30 is a locking bar 55 which, when in full lines position, permits the rotor 30 to rotate but when moved inward into the broken line position 56 locks the member 30 against rotation.

The operation of the cooling tower 10 is as 35 follows:

The locking bar 55 being in its full line position, water is sprayed through the pipe 50 to the 40 nozzle 51 so that this is sprayed over the distributing platform 52 and drops in a finely divided state downwardly onto the topmost element 38 of the rotor 30. This water drops from this element on downward and successively passes through all of the elements 38. The dropping water impacts 45 against the inclined upper surfaces 46 of the impeller baffle blades 45 so as to impart a rotating moment to the rotor 30. The rotor 30 is thus caused to rotate at a speed of from 10 to 20 revolutions per minute, which sets up a considerable draft of air in the cooling space 20. This 50 draft of air greatly increases the cooling effect of the air upon the water by side circulation through the passages between the louvres, the air being drawn through the passages immediately 55 above each rotor element, and passing downward through the opening 27 of the platform 22 thereadjacent, a portion of this air being then discharged outward between the louvres immediately below the rotor element, another portion 60 of this air moving downward through the rotor element immediately therebelow. In Fig. 1 I have illustrated by arrows 60 the circulation paths as set up by one of the rotor elements 38. I have found that a cooling tower of the type of 65 my invention can cool a much larger quantity of water than a cooling tower of the old type in which the water merely dropped through the tower and in which no means was provided for creating artificially a current of air in the tower.

70 It is also desired to point out that the stationary baffle boards 24 are inclined slightly inward so that water sprayed outward by the rotating tables 38, when falling on these stationary baffle boards, will be carried in through the ditches 25 to the edges of the various holes 27 where this

water will be permitted to drop downward through the current of air set up by the rotor 30.

I claim as my invention:

1. A cooling tower comprising: a frame open to the atmosphere; means for confining a liquid falling in a subdivided state through the atmosphere in the space defined by said frame; and means movable by the impact of said liquid thereagainst for accelerating the action of the atmosphere upon said liquid. 80

2. A cooling tower comprising: a frame open to the atmosphere; means for confining a liquid falling in a subdivided state through the atmosphere in the space defined by said frame; and means rotatable by the impact of said liquid thereagainst for accelerating the action of the atmosphere upon said liquid. 85

3. A cooling tower comprising: a frame open to the atmosphere; means for confining a liquid falling in a subdivided state through the atmosphere in the space defined by said frame; and means rotatable about a substantially vertical axis by the impact of said liquid thereagainst for accelerating the action of the atmosphere upon said liquid. 90

4. In a cooling tower, the combination of: a frame open to the atmosphere; a rotor element mounted for rotation in said frame; blades mounted upon said element; and means for dropping a liquid to be cooled onto said blades to cause rotation of said rotor element. 105

5. In a cooling tower, the combination of: means defining a cooling space; a rotor element rotatable in said cooling space, said means including louvres adjacent said rotor element, said louvres providing passages communicating with said cooling space and with the exterior of said cooling tower; blades on said rotor element adapted to circulate air through said rotor element and through said passages; and means for introducing the liquid to be cooled into the cooling space above said rotor element and allowing said liquid to drop onto said blades in a manner to turn said rotor element. 110

6. In a cooling tower, the combination of: means defining a cooling space; a platform extending across said space and having an opening therein; a rotor element rotatably mounted in a manner to substantially fill said opening, said means including louvres around said cooling space and providing a primary passage opening on that portion of said cooling space above said rotor element and providing a secondary passage opening on that portion of said cooling space below said rotor element; and interspaced blades 125 on said rotor element adapted when rotated to circulate air through said passages and through said opening. 130

7. In a cooling tower, the combination of: means defining a cooling space; a platform extending across said space and having an opening therein; a rotor element rotatably mounted in a manner to substantially fill said opening, said means including louvres around said cooling space and providing a primary passage opening on that portion of said cooling space above said rotor element and providing a secondary passage opening on that portion of said cooling space below said rotor element; and interspaced blades on 140 said rotor element adapted when rotated to draw air into said cooling space through said primary passage, move this air through said opening in said platform, and discharge said air from said cooling space through said secondary passage. 145

8. A combination as defined in claim 7 includ- 150

ing means for dropping water to be cooled onto said blades in a manner to rotate said rotor element, said water coming in intimate contact with said air passing through said cooling space under the influence of said blades.

5 9. In a cooling tower, the combination of: a frame through which passages air circulated by the rotation of said blades may pass.

10 a frame open to the atmosphere and providing a vertically disposed cooling space; a shaft rotatably mounted in said cooling space; a plurality of rotor elements secured to said shaft; a plurality of blades positioned on each of said rotor elements; and means for dropping water through said space in a manner to successively pass through said rotor elements, said blades being so inclined that the impact of said water thereon rotates said rotor elements and said shaft.

15 10. In a cooling tower providing a vertically disposed cooling space, the combination of: a series of platforms in said cooling space, each of said platforms having an opening therein; a shaft extending through said openings and free to rotate in said cooling space; a rotor element secured to said shaft adjacent each of said openings; inclined blades on said rotor elements; and means for introducing the liquid to be cooled into the top of said tower, said liquid passing successively through said rotor elements and exerting a force on said blades tending to turn said shaft.

20 11. In a cooling tower, the combination of: a frame open to the atmosphere and providing a vertically disposed cooling space; a plurality of rotor elements spaced along said cooling space and rotatably mounted therein; blades on each of said rotor elements; and means for introducing water into the top of said cooling space whereby said water may drop successively through said rotor elements, the impinging of said water on said blades tending to rotate said rotor elements.

25 12. In a cooling tower, the combination of: a frame open to the atmosphere and providing a vertically disposed cooling space; a plurality of rotor elements spaced along said cooling space and rotatably mounted therein; blades on each of said rotor elements; and means for introducing water into the top of said cooling space whereby said water may drop successively through said rotor elements, the impinging of said water on said blades tending to rotate said rotor elements, said frame, including inter-spaced louvres between each of said rotor elements providing passages communicating between said cooling space and the exterior of said

frame through which passages air circulated by the rotation of said blades may pass.

30 13. In a cooling tower, the combination of: a frame open to the atmosphere, portions of said frame providing a cooling space; a platform extending across said cooling space and providing an opening therein; a rotor element rotatably mounted adjacent said opening and having inclined blades; and means for introducing water into the top of said cooling space, said water dropping through said rotor element in a manner to rotate same.

35 14. A combination as defined in claim 13 in which said platform slopes downward toward said opening.

40 15. In a cooling tower, the combination of: a frame open to the atmosphere, portions of said frame forming a cooling space; a rotor element rotatably mounted in said cooling space and having inclined blades; said means including a distributing platform above said rotor element; and means for supplying water to the top of said distributing platform, said water passing therethrough and dropping onto said rotor element in a manner to turn same.

45 16. In a cooling tower, the combination of: a frame open to the atmosphere, portions of said frame forming a cooling space; a shaft extending through said space; a thrust bearing at the top of said shaft for supporting same from said means; a radial bearing in the lower end of said cooling space for journaling the lower end of said shaft; and a rotor element secured to said shaft between said bearings.

50 17. In a rotor element adapted to be rotated by water falling thereon, the combination of: a hub; spokes extending outward from said hub; braces extending between said spokes; and a plurality of parallel inclined blades between each pair of spokes, said blades being secured to said spokes and to said braces, said blades being similarly inclined relative to the direction of rotation.

55 18. In a rotor element adapted to be rotated by water falling thereon, the combination of: a hub; spokes extending outward from said hub; blades supported by said spokes; and struts extending downward from said spokes and being connected to the lower end of said hub, said struts tending to conduct the water passing through said blades toward said hub.
